UNITED STATES PATENT OFFICE.

LOUIS LE COMPTE AND JOSEPH LE COMPTE, OF AURORA, ILLINOIS, ASSIGNEES TO THE
LE COMPTE COMPANY, OF CHICAGO, ILLINOIS, A CORPORATION OF ILLINOIS.

COMBINED DRAW-HEAD AND AIR COUPLING.

1,140,382.

Specification of Letters Patent.

Patented May 25, 1915.

Application filed June 4, 1909. Serial No. 500,219.

To all whom it may concern:

Be it known that we, LOUIS LE COMPTE and JOSEPH LE COMPTE, citizens of the United States, and residents of the city of Aurora, in the county of Kane and State of Illinois, have invented certain new and useful Improvements in Combination Draw-Head and Air Couplings; and we do hereby declare that the following is a full, clear, and exact description of the same, reference being had to the accompanying drawings, and to the letters of reference marked thereon, which form a part of this specification.

This invention relates to improvements in combination draw head and air couplings adapted to couple automatically when brought together and simultaneously couple the air connections.

It is an object of this invention to provide a device of the class specified in which the draw heads are prevented from relative lateral movement to prevent uncoupling and prevent great stress being exerted on the knuckles but in which the drawheads are movable freely vertically.

It is further an object of this invention to provide pivotally mounted drawheads to which are secured the coupling knuckles and in which the knuckles can never become uncoupled even on the sharpest curves.

It is further an object of this invention to provide mechanism for automatically centralizing the draw heads on the radius bars but which are yieldable to permit the drawheads swinging.

It is further an object of this invention to provide pivotally supported valve casings on the drawheads and mechanism for wedging the same together to provide a tight connection when the drawheads are coupled.

It is further an object of this invention to provide mechanism for automatically opening the valves when the drawheads are coupled and mechanism for automatically closing the valves when the drawheads are uncoupled and holding the valves closed until the drawheads are again coupled.

It is also an object of this invention to provide a coupling that is adapted to couple with any type of M. C. B. coupler.

It is further an object of this invention to provide a device of the class described which is simple in construction, cheap to manufacture and which is applicable to

steam roads, interurban, street or elevated railroads.

The invention consists of the matters hereinafter described and more fully pointed out and defined in the appended claims. 60

In the drawings: Figure 1 is a side elevation of a device embodying our invention showing the drawheads in coupled relation. Fig. 2 is a top plan view thereof. Fig. 3 is a bottom plan view of the device. Fig. 4 is 65 a view illustrating a draw head embodying our invention coupled with a drawhead of the M. C. B. type, the latter of which is shown in dotted lines. Fig. 5 is a central horizontal section. Fig. 6 is a central vertical section. Fig. 7 is a section on line 7—7 of Fig. 6. Fig. 8 is a section on line 8—8 of Fig. 6. Fig. 9 is an enlarged detail illustrating the means for limiting the swinging movement of one of the valve casings. Fig. 10 is a section on line 10—10 of Fig. 8. Fig. 11 is an enlarged detail of the centralizing means for the drawheads. 70

As shown in the drawings: A—A¹, indicate the draw bars, to each of which is integrally or otherwise rigidly connected a yoke a. Each drawhead comprises a casing B, having an integral lug b, adapted to engage between the arms a¹, of the yoke and are pivotally secured thereto by means of a pin 80 b¹, which is held from displacement by means of a cotter pin b², or nut. As shown, the distance between the arms a¹, is sufficiently greater than the thickness of the lugs b, to permit the required vertical movement of the draw heads and a spring b³, is secured on the pin b¹, between the lower arm a¹, and lug b, to centralize the heads, thereby adapting them to move either upwardly 85 or downwardly against compression of the spring. 90

For centralizing the drawheads or normally holding the same in alinement with the draw bars to facilitate coupling, recesses are provided in a wall of each casing B, and fitting therein are pins b⁴, which at their outer ends bear against the yoke and at their inner ends are each provided with a pushing spring b⁵, the opposite end of which bears against the wall of the casing. 100

Each casing B, as shown, is provided with a coupling knuckle B¹, which, as shown in Fig. 4, is shaped on its inner side to couple with any type of M. C. B. coupler. Said knuckles are each provided with a notch b⁶, 110

adapted to register with an aperture in the opposite casing when the drawheads are in coupled relation. An aperture b^7 , is also provided in each casing for purposes herein-after set forth. A bar b^8 , integral with the knuckle and casing firmly braces each knuckle and affords great strength.

Means are provided for locking the knuckles or rigid draw hooks B^1 to the casings B , comprising a locking member C , having inwardly directed catches $c-c^1$, adapted to be engaged by the rounded or cam face of the knuckles or draw hooks, so as to be automatically adjusted outwardly to permit the knuckles entering the respective casing after which the catch c , enters the aperture b^7 , in the casing at the base of the knuckle and the catch c^1 , enters the aperture in the casing and recess b^6 , in the knuckle. The faces 20 of the casings abut and prevent relative swinging movement of the knuckles and thereby prevent all possibility of the knuckles becoming detached.

Each locking member is provided with a bolt c^2 , which engages in a passage in the top of the casing and a pushing spring c^3 , is secured in a longitudinal slot in the bolt and bears against one end of the slot and a pin c^4 , rigidly secured to the wall of the casing thereby normally holding the locking member in locking position.

For the purpose of uncoupling the drawheads a lever D , is pivoted to each casing or draw head by means of a pivoted pin d^1 and projects into the same at the base of the knuckle. Said lever is provided with a cam or tooth which engages in a cam slot in the adjacent bolt c^2 (see Fig. 7). A chain d^1 , or other connection is secured at one end to 40 the lever D , and at its opposite end is connected to an adjusting rod d^2 . Each lever D extends through an aperture b^7 and is provided with a projecting boss or stud d^2 , shown in Fig. 7. The catch portion c of the locking member C of the mating draw head is adapted to enter said aperture b^7 , as shown in Fig. 5 and as herein elsewhere described, and is thus in position to be engaged and operated or moved to releasing position by the stud d^2 on the adjacent lever D . Each lever D is thus adapted to operate the locking members C of both draw heads simultaneously so as to release or unlock the draw heads.

55 A valve casing or coupler shoe E , is pivoted by means of a suitable stud e , to the bottom of each drawhead B , to have a limited swinging movement on its axis laterally or transversely with respect to the draw head, such pivoted coupler member or shoe being supported by the draw head and movable independently of the draw head connecting or locking mechanism and is limited in its movement by means of a pin e^1 , secured to the wall of the drawhead B , which

engages in a suitable slot in the casing E , as shown in Fig. 9. Each casing is apertured to receive any suitable number of connections, as shown however, three pipes $F-F^1-F^2$, are provided for the signal, brake and service. Opposite from said pipes and in alinement therewith are suitable passages in which are seated rubber packing members $f-f^1-f^2$, having a restricted axial passage for the admission of the air therethrough as shown clearly in Figs. 6 and 8. A valve is provided in each casing comprising a stem G , provided with apertures therethrough to afford communication between the respective pipes $F-F^1-F^2$, and passage in the members $f-f^1-f^2$.

Wedge members $H-H^1$, are secured to the drawheads adapted to engage the pivoted valve casings when the drawheads are being coupled and wedge the same tightly together to form a tight joint between the valve casings in which position the axial passages in the packing members in one valve casing are registering with the axial passages in the packing members $f-f^1-f^2$, in the other valve casing.

A lever g , is secured to each valve stem G , which is engaged by a pin g^1 , on the valve casing of the opposite drawhead, when the drawheads are being coupled, and rotates the stem to adjust the passages therein to afford communication between the pipes $F-F^1-F^2$, and passages in the packing members $f-f^1-f^2$. A torsion spring g^2 , is seated in a recess in each valve casing and is connected at one end to the stem G , and at its opposite end to the valve casing adapted to automatically adjust the stem to close the pipes when the drawheads are uncoupled.

The operation is as follows: The drawheads are held centralized adapting the heads to be automatically coupled without manual adjustment of the same. When the drawheads are brought together the cam faces of the knuckles successively engage the catches $c-c^1$, to release the catch to permit insertion of the knuckles into the casings and the springs c^3 , adjust the locking members to engage the knuckles and drawheads to rigidly secure the drawheads together. It is obvious that the union of the drawheads is not a pivotal connection and therefore no stress can be exerted on the knuckles or draw hooks. Also the drawheads are free to move upward or downward and normally are centralized vertically by the springs b^3 . As the drawheads are coupled the respective wedge member H or H^1 , each engages the inclined face of the pivoted valve casing attached to the opposite drawhead and the valve casings are therefore forced tightly together. At the same time the pin g^1 , on one valve casing engages the lever g , attached to the valve in the opposite valve casing and adjusts the valve stem to open the valve and afford com-

munication between the pipes in one car to the pipes in the adjacent car. The valves are held open as long as the cars are coupled. When uncoupling the levers D, are actuated 5 releasing the locking members C, from the knuckles permitting the retraction of the knuckles from the drawhead casings. As the drawheads are uncoupled the pins g¹, are withdrawn from their lever g, permitting the 10 torsion spring g², for each valve to adjust the valve to close the train pipes and hold the same closed until the drawheads are again coupled.

In Fig. 4, a standard M. C. B. drawhead 15 is shown in dotted lines in which the knuckle is adapted to engage the knuckle B¹, and the catch c¹, bears against the knuckle of the M. C. B. drawhead holding the same in coupled relation.

20 Inasmuch as the drawheads are pivoted to the draw bars and the knuckles are non-pivoted, said knuckles can never uncouple on any curve or under any circumstances except by first actuating the levers D.

25 Numerous details of construction may be varied, and we do not desire to limit this application for patent otherwise than necessitated by the prior art.

We claim:

30 1. In a device of the class described the combination of a draw head, connecting mechanism adapted to connect said draw head in rigid relation to a similar draw head, a coupler shoe having a side opening 35 and pivotally mounted upon and supported by and movable transversely on its axis with respect to the draw head independently of the draw head connecting mechanism, and adapted to be held in engagement with a 40 similar coupler shoe of a mating draw head by said connecting mechanism, a boss mounted adjacent to the pivoted coupler shoe, said coupler shoe and boss being so constructed and arranged as to admit there- 45 between and engage the coupler shoe of a mating draw head, and a conduit in said side opening of the coupler shoe and movable with the latter into operative engagement with a similar conduit of a mating 50 coupler shoe.

2. In a device of the class described the combination of a pair of draw heads, a coupler shoe pivotally supported by and movable on its axis transversely with respect to 55 each draw head, respectively, each of said coupler shoes having a side opening adapted to communicate with a similar side opening of a mating coupler shoe, a hose pipe supported by and movable with each coupler 60 shoe, respectively, transversely with respect to the draw heads, and each forming a passage communicating with one of said side openings, a boss mounted adjacent to the pivoted coupler shoe of each draw head, re- 65 spectively, said coupler shoe and boss of

each draw head being so constructed and arranged as to admit therebetween and engage the coupler shoe of a mating draw head to hold the coupler shoes in position to present the side openings thereof in position to communicate with each other, and connecting mechanism mounted on each draw head, respectively, and movable independently of the coupler shoes, for connecting said draw heads in rigid relation to each other. 70 75

3. In a device of the class described the combination of a pair of draw heads, a coupler shoe mounted on and movable transversely with respect to each draw head, a 80 hose pipe supported by and movable with each coupler shoe transversely with respect to the draw heads and into and out of position to communicate with the hose pipe of an opposite coupler shoe, a boss mounted 85 adjacent to the pivoted coupler shoe of each draw head, respectively, said coupler shoe and boss being so constructed and arranged as to admit therebetween and engage the coupler shoe of a mating draw head, valve 90 mechanism on each coupler shoe, for opening and closing the passages formed by said pipes, means for automatically operating the valve mechanism, and locking mechanism mounted on each draw head, respectively, and movable independently of the coupler shoes into and out of locking engagement with the opposite draw head and adapted to connect the draw heads in rigid 95 relation to each other. 100

4. In a device of the class described, the combination of a pair of draw heads, a coupler shoe pivotally mounted on and movable transversely with respect to each draw head, a hose pipe supported by and movable with each coupler shoe transversely with respect to the draw heads, a passage in each coupler shoe adapted to communicate with the corresponding hose pipe in the same coupler shoe, a valve in each coupler shoe, a valve 110 operating lever connected with each valve, a boss on each coupler shoe adapted to engage the valve operating lever of the opposite coupler shoe, and means for rigidly connecting the draw heads. 115

5. In a device of the class described, the combination of a pair of draw heads, a coupler shoe pivotally mounted on and movable transversely with respect to each draw head, a hose pipe supported by and movable with each coupler shoe transversely with respect to the draw heads, a valve on each coupler shoe for opening and closing the passage formed by the hose pipe, a lever on each valve, movable into and out of engagement 120 with a valve-operating member located on the opposite coupler shoe, a boss mounted adjacent to the pivoted coupler shoe of each draw head, respectively, said coupler shoe and boss being so constructed and arranged 125 130

as to admit therebetween and engage the coupler shoe of a mating draw head, and connecting mechanism mounted on each draw head, respectively, and movable independently of the coupler shoes into and out of coupling position.

6. In a device of the class described, the combination of a pair of draw heads, a coupler shoe pivotally mounted on and movable 10 transversely with respect to each draw head, a plurality of hose pipes supported by and movable with each coupler shoe, a valve in each coupler shoe provided with a plurality of passages each adapted to communicate 15 with one of the hose pipes on the shoe on which the valve is located, a valve operating

lever connected with each valve and movable into and out of engagement with a valve operating member on the other coupler shoe, a boss on each draw head adapted to 20 engage the coupler shoe of the opposite draw head, and means for rigidly connecting the draw heads.

In testimony whereof we have hereunto subscribed our names in the presence of two 25 subscribing witnesses.

LOUIS LE COMPTÉ.
JOSEPH LE COMPTÉ.
